DESIGN FOR A REFRIGERATOR CABINET

John H. Benson, Salem, Ohio, assignor to Mullins
Manufacturing Corporation, Salem, Ohio, a
corporation of New York

Application March 16, 1944, Serial No. 112,933

Term of patent 7 years

(Cl. D67—3)

To all whom it may concern:

Be it known that I, John H. Benson, a citizen
of the United States, residing at Salem, in the
county of Columbiana and State of Ohio, have
invented a new, original, and ornamental Design
for a Refrigerator Cabinet, of which the follow-
ing is a specification, reference being had to the
accompanying drawing, forming part thereof.

The figure is a perspective view showing the

front, top and one side of an ornamental design
for a refrigerator cabinet embodying my new
design; the other side, not shown, is substantially
like the side shown.

I claim:

The ornamental design for a refrigerator cab-
inet, as shown and described.

JOHN H. BENSON.
